UNITED STATES PATENT OFFICE.

CHAUNCEY THOMAS, OF BOSTON, MASSACHUSETTS.

DESIGN FOR A CAB-BODY.

SPECIFICATION forming part of Design No. 29,678, dated November 15, 1898.

Application filed September 6, 1898. Serial No. 690,340. Term of patent 14 years.

To all whom it may concern:

Be it known that I, CHAUNCEY THOMAS, a citizen of the United States, residing in Boston, in the county of Suffolk and State of Massachusetts, have invented and produced a new and original Design for a Cab-Body, of which the following is a specification.

Figure 1, in side elevation, represents a cab-body illustrating my design, the shafts being broken off, and Fig. 2 is a top view of the dashboard.

The leading feature of my design consists of a cab-body, substantially as herein shown and described, wherein the hood A surmounts the body proper, the latter having side panels B, the lower edge *b* of each panel being curved and sweeping forward and upward in an uninterrupted curved line, merging into the upright edge portion *d* of the dashboard D. The upper edge *b'* of the side body-panel springs from the point 3, with a reverse curve converging toward the curve of the lower edge *b*, and sweeps upward in a continuous curve, merging into the edge of the dashboard.

The shaft S has a brace *f*, the lower edge of which is formed as a reverse curve tangent at its ends to the under side of the shaft and the bottom of the dropped part of the body B', respectively.

The upright curved edge portions *d* of the dashboard are extended inward, and the body of the dashboard between them is concavo-convex, with flattened portions *d'* adjacent the edge portions *d*.

The design presents an exceedingly graceful effect to the eye of combined lightness and solidity.

Having fully described my design, what I claim is—

The design for a cab-body, substantially as herein shown and described.

In testimony whereof I have signed my name to this specification in the presence of two subscribing witnesses.

CHAUNCEY THOMAS.
